ADJUSTABLE NOZZLES

Henry J. Kachergis, Waterbury, Conn., assignor, by
mesne assignments, to Otto Bernz Company, Inc.,
Rochester, N.Y., a corporation of New York

Filed Aug. 26, 1958, Ser. No. 757,274

5 Claims. (Cl. 239—458)

This invention relates to spray nozzles such as are used on lawn sprinklers or as a garden hose nozzle.

It is desirable at times to have a spray nozzle which will produce a substantially flat fan-type of spray or at other times, a solid jet stream without appreciably changing the volume of the projected stream. Such a nozzle is particularly useful in association with the so-called knock-about or impulse type sprinklers of the general character shown in my prior application, Serial Number 585,119, issued as patent 2,853,342. Impulse sprinklers are generally used for sprinkling lawns or relatively small areas as well as larger areas, such as golf lots and agricultural fields, but there has been no suitable nozzle that will project a long jet stream for the larger areas or a short stream for the smaller areas unless the amount of discharged fluid was measurably restricted.

It is the object of this invention to provide a very simple, efficient and economical form of nozzle for producing a fan-type or other form of wide spray for smaller areas and a jet type of stream for larger areas without affecting or valving off the amount of discharged fluid.

These and other objects and advantages of the invention will be disclosed in the following description taken in connection with the accompanying drawings, in which:

Fig. 1 is a side view of an impulse type sprinkler showing a nozzle embodying my invention attached thereto;

Fig. 2 is a cross-sectional view of the nozzle shown in adjusted position to produce a fan-type spray;

Fig. 3 is a similar view with the nozzle adjusted to produce a solid jet stream.

Fig. 4 is an end view of the discharge end of the nozzle;

Fig. 5 is a sectionalized perspective view of the bushing that is carried by the adjustable sleeve; and,

Fig. 6 is a perspective view of the discharge end of the nozzle stem.

Referring now to the drawing, the numeral 10 designates generally my improved nozzle which in Fig. 1 is shown as attached to the body 11 of an impulse sprinkler having the usual swinging arm 12 on its upper end and a deflector vane 13 pivoted at the outer end of said arm. The deflector vane 13 is adapted, when impinged by the stream of water coming from the nozzle 10, to cause the arm to swing to one side or the other of the nozzle axis against the influence of a spring 14 which serves to return the arm to normal position where a shoulder 15 on said arm will strike an abutment stop 16 on the body 11 and cause the latter to intermittently rotate about its axis.

The nozzle 10 embodying my invention consists of a hollow stem 20, an adjustable sleeve 21, a bushing 22 rotatably carried by said sleeve and a lock nut 23. Specifically, the stem 20 has a threaded section 24 at one end which is adapted to be threaded into a biased boss 11a on the body 11 for attaching the nozzle to

2

the sprinkler and then locked in place by the lock nut 23. Ahead of the threaded section 24 is another threaded section 26 to which is threadedly engaged the sleeve 21 for the purpose of adjusting the said sleeve longitudinally of the stem 20. The bushing 22 is fitted into a counterbore 27 in the sleeve 21 and held in place by a washer 28 secured to the outer end of such sleeve as by a spun-over flange 29. It should be understood that the bushing 22 is rotatable in the counterbore 27 so that sleeve 21 may rotate relative thereto for reasons as will appear later.

In order to produce either a fan-type of spray or a jet stream form the nozzle 10, the outer end of the stem is formed with an inward flange 30 surrounding a central orifice 31 and a pair of diametrically opposed slots 32 in the stem wall that extend through the flange 30 and intercept said central orifice 31. The bushing 22 is provided with longitudinal ribs 33 adapted to slidably engage in the slots 32, and said ribs are formed at their outer ends with inward lugs 34 serving to close up that portion of the slots 32 that extend through the end of the flange 30. Also, it will be noted from Fig. 5 that the terminal end of the lugs 34 are arcuately shaped so as to conform to the size and shape of the central orifice 31 so that when the sleeve 21 is advanced to its foremost position as shown in Fig. 3, it completes the circumference of the orifice 31.

To provide a leak-proof sealing between the sleeve 21 and the stem 20, the stem has intermediate its length 30 circumferentially spaced ribs 35 providing an annular groove 36 therebetween within which is loosely fitted a flip ring 37 having sealing engagement with the center bore of said sleeve.

In the operation of the nozzle to provide a fan-type of spray, it is only necessary to rotate the sleeve 21 so as to move the bushing 22 inwardly from the discharge end of the stem 20, i.e., to the position shown in Fig. 2. In approaching this position, it will be noted that the lugs 34 move axially inwardly and clear the forward end of the opposed slots 32 so that fluid can pass through the orifice 31 as well as through the open end of said slots.

When my nozzle is used with a sprinkler of the type shown in Fig. 1 for the purpose of producing a fan spray, it is preferable to have the opposed slots 32 in the stem 20 arranged in a vertical position. If used on other types of sprinklers, or as a hose nozzle, the position of the slots 32 can be arranged in any position to suit the needs of the area to be sprinkled, and the adjustment of the nozzle being held in locked position by the lock nut 23.

If it is desired to produce a long jet stream from the nozzle to irrigate larger areas, it is only necessary to adjust the sleeve 21 to its foremost position on the stem as seen in Fig. 3 in which position, the lugs 34 will close up the forward end of the slots 32 and provide a complete round orifice 31 at the discharge end of said nozzle. The ribs 33 and the integral lugs 34 engaging in the opposed slots 32 will allow the bushing to move lengthwise of the stem 20 while the sleeve is rotated on said stem to adjust the bushing. When the sleeve 21 is adjusted to various intermediate positions, any desired range may be obtained between the maximum width fan spray and a plain jet stream.

While only one form of the invention has been here disclosed, it will be understood that modifications may be made to vary the character of the streams produced by the nozzle, as for instance, the sleeve 21 may be constructed with only one slot 32 intercepting the center orifice 31, or it may be constructed with three slots equally arranged thereabout and with the appropriate

bushing 22 to produce a more diversified or widened type of spray, all of which constructions will come within the scope of the invention as defined in the following claims.

What is claimed:

1. A nozzle comprising a hollow nozzle stem having means at one end for attachment to a fluid supply, the opposite end of said stem having a restricted orifice opening through said end in axial alignment with the stem and one or more slots intercepting said orifice and extending lengthwise through the wall of said stem, a sleeve adjustable longitudinally on said stem, a bushing carried within said sleeve, and means on said bushing serving to close said one or more slots when the sleeve is moved to an outer position to produce a jet stream of fluid and to progressively open said one or more slots as the sleeve is moved to an inner position to produce a widened spray of fluid.

2. A nozzle comprising a hollow nozzle stem having means at one end for attachment to a fluid supply, the opposite end of said stem having a restricted round orifice opening through said end in axial alignment with the stem and one or more slots intercepting said orifice and extending lengthwise through the wall of said stem, a sleeve adjustable longitudinally on said stem, a bushing interposed between the stem and sleeve and having ribs slidable in said slots, and lugs extending radially inwardly from the ends of said ribs and dimensioned to close up the slots where they intercept the round orifice at the end of the nozzle when the sleeve is moved toward its outward position to produce a solid jet stream.

3. A nozzle member comprising a hollow stem having means at one end for attachment to a fluid supply, the opposite end of said stem having a closed end with a central circular orifice and having one or more slots 10 in its sidewall, said slots intercepting said central orifice, a sleeve adjustable longitudinally on said stem, a bushing carried by said sleeve, lug means on said bushing slidable in said slots for maintaining said bushing in non-rotatable connections with said stem, said lug means 15 cooperating with said slots and said end orifice whereby the combined areas of said slots and end orifice may be varied by movement of said sleeve on said stem to gradually vary the character of the discharge fluid from a diversified type of spray to a solid jet and vice-versa.

4. A nozzle as defined in claim 3 wherein the slots of said stem are a pair of diametrically opposed slots serving to produce a fan-type of spray when the bushing is adjusted to its innermost position.

5. A nozzle member as defined in claim 3 wherein 20 the terminal ends of the lugs are of arcuate shape to conform with the circular orifice.
